[57] CLAIM

The ornamental design for a multi-cell battery charger, as shown.

DESCRIPTION

FIG. 1 is a perspective view of the multi-cell battery charger showing our new design;

FIG. 2 is a top plane view of the battery holder forming a part of the multi-cell battery charger;

FIG. 3 is a side elevational view of the battery holder;

FIG. 4 is a rear elevational view of the battery holder;

FIG. 5 is a top plane view of the electrical plug member of the multi-cell battery charger;

FIG. 6 is a side elevational view of the electrical plug member;

FIG. 7 is a front elevational view of the electrical plug member; and

FIG. 8 is a bottom plane view of the multi-cell battery charger.
